REFRIGERATOR DOOR LOCK

Herbert D. Squire, Galesburg, Ill., assignor to Midwest Manufacturing Corporation, Galesburg, Ill.

Application February 7, 1957, Serial No. 638,873

4 Claims. (Cl. 70—149)

This invention relates to refrigerators and more particularly to improvements in locks for locking the refrigerator doors.

Although heretofore it has been proposed to provide locks for refrigerator doors, these were usually specially constructed in order to effect the desired results. Furthermore, such locks frequently made it impossible to open the door when the door was locked, which condition is undesirable where safety means is provided inside the door for permitting the door to be opened from inside the refrigerator.

By the present invention I have provided a locking means for a refrigerator door which can be used in conjunction with the standard latching means, no change being necessary thereto. Thus, a single door latch may be provided for various types of doors or the lock can be installed on existing doors without changing the latch.

In the drawings:

Fig. 1 is a vertical elevational view of a fragment of a door latch and the locking means, the front door panel and support for the door handle being shown in section; and support for the door handle being shown in section;

Fig. 2 is a fragmentary section on the line 2—2 in Fig. 1 looking in the direction of the arrows and showing an alternate position of the parts by dotted lines;

Fig. 3 is an inside elevational view of the latch per se as shown in Fig. 1;

Fig. 4 is a perspective view of the latch locking link; and

Fig. 5 is a view similar to Fig. 1 of the upper portion of the apparatus illustrating the same in locked positions.

Briefly, the invention includes a latch mechanism which is provided with a latch release member, the latch release member being connected to a movable link carried by a handle secured to the door, a key operated cam being provided for moving the link to a position where it is ineffective to open the door.

More particularly the latch may be of the construction shown in my copending application Serial No. 619,517, filed October 31, 1956. It includes a bolt 10 (Fig. 3) which cooperates with a keeper, not shown, to hold the latch in closed position and a release cam 12 which may be pushed or pulled to release the bolt 10 so that the door may be opened. As explained in the copending application, the latch may be operated by means other than that illustrated herein, this being the preferred form however.

Operating means for the cam is provided in the form of a rod 14, the lower end of which is provided with a hook 15 (Fig. 1) that engages the member 12. Upward movement of the rod 14 moves the cam 12 which causes the cam surface 16 to release the bolt.

Spaced from the latch, and usually upwardly thereof, the door panel 20 is provided with a housing 21 secured thereto in which a handle 22 is pivotally journaled on a pin 23. The handle 22 is provided with an outward and upwardly extending finger gripping portion 24 while the inner portion of the handle extends inwardly of the front panel at 25. A cup-shaped rubber gasket 26 is provided

to seal the opening in the door through which the portion 25 of the handle extends.

The inner end of the handle 25 has secured thereto, by a shoulder screw 30, a link 31. The link 31 is in the form of a generally rectangular plate, being provided with a lower extension 32 having an offset flange 33 thereon provided with an opening through which the rod 14 extends. Upwardly of the flange 33 the link is provided with an inverted L-shaped opening 35, the upper part of which provides a shoulder 36 and forwardly thereof an opening 37 which extends downwardly. The rod 14 is provided with an offset end 38 which extends through the opening and is held therein because it is guided by the flange 33. Normally the offset end seats on the seat 36.

Under these conditions the handle may be moved to the position shown in dashed lines, which movement is transmitted by the link 31 from the shoulder 36 to the end 38 of the rod 14 to pull the cam member upwardly and release the latch.

The link is also provided with an extension 40 which extends toward the front door panel and is provided with a laterally extending flange 41.

Mounted on the door below the housing 21 is a lock 25 which includes a barrel 45 and inner and outer locking nuts 46 and 47. The barrel can be of any standard type construction and is provided with an inner member 48 which may be turned by a key 49. The inner rotary member has a generally oval shaped cam 50 secured thereto by a screw 51. As can best be seen in Fig. 2 when the key is rotated the cam, which is eccentrically mounted on the rotary portion 48, moves upwardly to move the flange 41 upwardly and with it the link 31, as best shown in Fig. 5. The link normally rests in the position shown in Fig. 1; this position may be maintained by gravitational forces. I have found, however, that a spring 60 having an end 61 hooked in a hole 62 in the link and the other end connected to the frame 63, that supports the latch, assures that the link, when released, will be in the position shown in Fig. 1 under normal conditions.

When the key is rotated to pivot the link to the position shown in Fig. 5, the end 38 of the rod 14 is then moved over by the flange 33 and disposed in alignment with the downwardly extending continuation 37 of the opening 35. In this position should the handle be operated, the end 38 of the link slides freely in the opening 37 and the operating member 14 is not moved in the upward direction and therefore the latch remains closed. It will be seen, however, that there is nothing to hinder the operation of the latch under these conditions for the release by a safety release such as shown in my copending application Serial No. 619,445, filed October 31, 1956, now Patent No. 2,823,940, issued February 18, 1958.

It will be apparent therefore that no changes need be made in the latch mechanism and that the only addition necessary is the substitution of the link 31 between the rod 14 and the handle 25 and the addition of the locking cam to the door below the handle. The device is operative, however, when locked to prevent access to the contents of the refrigerator by unauthorized persons.

Having thus described my invention, I am aware that numerous and extensive departures may be made therefrom without departing from the scope of my invention as defined by the appended claims.

I claim:

1. In a door lock for a door which carries a door holding latch and a movable operating member spaced from the latch, the improvement which comprises a link pivotally connected to said operating member, a movable rod extending from said link toward the latch and coupled to

the latch to operate the same, said link having a slot therein which receives the rod, said slot having a laterally offset portion which defines a shoulder for engagement by the rod which extends transverse to the direction of movement of the rod and an elongated portion which extends from said offset portion in the direction of movement of the rod, a movable key-operated cam on the door engaging said link and defining a pivot for the link when the link is moved by the operating member, and unitary spring means biasing the link against the cam in all positions of the cam and biasing the link toward the latch, said operating member being movable to pivot the link about the cam against the bias of said spring means to move the rod with respect to said latch when the rod engages said shoulder on the link, and said cam being movable to pivot the link about its pivotal connection to said operating member to move said shoulder laterally away from the rod and position said elongated portion of its slot receiving the rod so that the rod remains stationary upon movement of the handle to pivot the link about the cam in this position of the cam.

2. In a door lock for a door which carries a door holding latch and a movable operating member spaced from the latch, the improvement which comprises a link pivotally connected to said operating member, a movable rod extending from said link toward the latch and coupled to the latch to operate the same, said link having a slot therein which receives the rod, said slot having a laterally offset portion which defines a transverse shoulder facing away from the latch for engagement by the rod and an elongated portion which extends from said offset portion toward the latch, a movable key-operated cam on the door engaging said link and defining a pivot for the link when the link is pivoted by the operating member, and unitary spring means biasing the link into engagement with the cam in all positions of the cam and biasing the link toward the latch, said operating member being movable to pivot the link about the cam against the bias of said spring means to pull the rod away from said latch when the rod engages said shoulder on the link, and said cam being movable to pivot the link about its pivotal connection to said operating member to move said shoulder laterally away from the rod and position said elongated portion of its slot receiving the rod so that the rod remains stationary upon movement of the operating member to pivot the link about the cam in this position of the cam.

3. In a door lock for a door which carries a door holding latch and a handle pivotally mounted on the door in spaced relation to the latch, the improvement which comprises a link pivotally connected to the inner end of the handle, a movable rod extending from said link toward the latch and coupled to the latch to operate the same, said link having a slot therein which receives the rod, said slot having a laterally offset portion which defines a transverse shoulder facing away from the latch

for engagement by the rod and an elongated portion which extends from said offset portion toward the latch, a rotatable key-operated cam on the door presenting a cam surface which engages said link and defines a pivot for the link, and a spring biasing the link into engagement with the cam in all positions of the cam and biasing the link toward the latch, said handle when pivoted in one direction pivoting the link about the cam to pull the rod away from said latch when the rod engages said shoulder on the link, and said cam being rotatable to pivot the link about its pivotal connection to the handle to move said shoulder laterally away from the rod and position said elongated portion of its slot receiving the rod so that the rod remains stationary upon pivoting of the handle in said one direction to pivot the link about the cam in this position of the cam.

4. In a door lock for a door which carries a door holding latch and a handle pivoted on the door above the latch and extending into the door, the improvement which comprises a link pivotally connected at its upper end to the inner end of the handle, a rod extending down from said link toward the latch and coupled at its lower end to the latch to operate the same, said link having an inverted L-shaped slot therein spaced below its pivotal connection to the handle comprising an upper laterally offset portion presenting an upwardly facing transverse shoulder and a vertical portion which extends down from said offset portion forwardly of said shoulder, said rod having a transversely extending upper end which is received in said slot, a rotatable key-operated cam on the door having a peripheral cam surface which engages beneath the link forward of said vertical portion of the slot and defines a pivotal support for the link, and a tension spring exerting a downward pull on the link between the latter's pivotal connection to the inner end of the handle and said cam surface to maintain the link engaged against said cam surface in all positions of the cam, said handle when the upper end of the rod engages said shoulder being pivotable in one direction against the pull of said spring to pivot the link about the cam to pull the rod up away from the latch, and said cam when turned pivoting the link about its pivotal connection to the handle to move said shoulder laterally away from the upper end of the rod and position said vertical portion of the slot receiving the upper end of the rod so that the rod remains stationary upon pivoting of the handle in said one direction to pivot the link about the cam in this position to which the cam has been turned.
